CLAIM

The ornamental design for a food processing attachment, as shown and described.

DESCRIPTION

FIG. 1 is a front-right perspective view of a food processing attachment according to the design; and,

FIG. 2 is a back-right perspective view thereof.

Dash-dot-dash broken lines are environmental only and form no part of the claimed design.

The portions of the article shown in even broken line form no part of the claimed design with broken lines adjacent un-shaded areas representing bounds of the claimed design.

1 Claim, 2 Drawing Sheets

Related U.S. Application Data

continuation of application No. 29/732,296, filed on Apr. 23, 2020, now Pat. No. Des. 939,272, which is a continuation of application No. 14/983,735, filed on Dec. 30, 2015, now Pat. No. 10,820,735.
